UNITED STATES PATENT OFFICE.

HARRY H. PORTER, OF LOS ANGELES, CALIFORNIA.

REGISTER-PLUG FOR MOUNTED COLOR-CUTS.

No. 893,194.

Specification of Letters Patent.

Patented July 14, 1908.

Application filed April 5, 1907. Serial No. 366,575.

To all whom it may concern:

Be it known that I, HARRY H. PORTER, a citizen of the United States, residing at Los Angeles, county of Los Angeles, and State 5 of California, have invented new and useful Improvements in Register - Plugs for Mounted Color-Cuts, of which the following is a specification.

In color plate work after the first color is 10 printed it frequently happens that the weather changes, sometimes it is more moist and the paper fulls up or increases slightly in size. At other times it is drier and the paper shrinks slightly. In both 15 cases it throws the color plate in the form out of register with the first print and the plate must be changed in the form till it registers. This change has been made heretofore by unlocking the form and changing 20 leads and copper spacers until a register was obtained. Then in locking the form again it frequently happened that the locking means had more pressure on one side than the other and the cut would still not register, 25 and the forms had to be unlocked and a new adjustment made. With my improved register plug this uncertainty can be avoided as the color cuts can be shifted without unlocking the form, thereby saving time, as 30 the distance the cut will have to be moved is accurately determined by the turning of a screw bolt forming a part of the plug.

My invention relates to means for accurately securing color cuts in the form, so 35 that the same can be removed and a new color cut inserted therein and held in register at the proper place without any danger of making a mistake; and the object thereof is to provide a simple and efficient device 40 which can be quickly operated for that purpose. I accomplish this object by the device described herein and illustrated in the accompanying drawings in which;

Figure 1 is a fragmentary view of a chase 45 with furniture secured therein and a color cut secured in a proper register by means of my improved register plug. Fig. 2 is a perspective view of the register plug detached. Fig. 3 is a perspective of the operating lever 50 for operating the binding bar of the plug. Fig. 4 is a cross section on the line 4—4 of Fig. 2. Fig. 5 is a longitudinal section on the line 5—5 of Fig. 4. Figs. 6, and 7, and 8 are perspective views of different parts of the 55 plug.

In the drawings 10 is the chase of ordinary

construction and 9 is the furniture which is secured therein by the ordinary quoins 11 in the usual manner.

12 is the color plate which is secured in the furniture by means of my improved register plug 13. This register plug consists of the following parts. The body A is preferably of a shape in which the faces except one are parallelograms, and is provided with a transverse bore B therethrough in which is longitudinally movable the bearing bar C. This bar is provided with a head D, the face of which is preferably knurled. In one side of the bearing bar is a spline E, and in the body 60 is a semi-circular channel F or spline-way into which the spline is received to prevent the bar from rotating in the body. The bar is provided with a central bore H, which is 65 interiorly threaded. In this bore is received a screw-threaded bolt I which has a head J in which are cut channels K. The bore B of the body is enlarged at one end sufficiently to chamber the head J of the bolt I, and one side of the body is cut away as best shown in 70 Fig. 7, so that the operating lever L can be inserted in the slots K, so that the screw I 75 may be rotated. The bar C is placed in the bore of the body from the side opposite the cut away portion. Bolt I is then screwed 80 into the bearing bar C, cap plate M is then secured upon the body, when the completed 85 register plug is ready for use.

In the operation of my device the color plate is placed within the furniture after the 90 same is secured in the chase in the usual manner. At the sides of the color plate and near each end thereof are placed register plugs and at the ends are like register plugs as shown in Fig. 1. It will be observed that 95 by the use of lever L the bearing bars can be rotated in either direction, that when rotated in one direction they will firmly bind the color plate in the furniture, and when rotated in the reverse direction they will 100 quickly release the same so that the plate can be removed. It will also be observed that by releasing the bearing on one side and end that when a new color plate is put in the furniture that by tightening up the bars that 105 were released the new color plate will be secured in register in the exact position of the former color plate. It will also be observed that as these register plugs are all constructed exactly alike the operator has means to 110 quickly and accurately change the position of any new color plate that he puts in, be-

cause by rotating the bearing bars the same distance, the color plate is held in the furniture at that changed distance. In rotating the bearing bars he would place the operating lever in one of the slots K and would move it until the lever contacted with the body. These slots and the cut away portion of the body adjacent to the head of the screw are preferably so arranged that two slots are susceptible of entry by the operating lever, whereby the bearing bar can be moved a certain pre-determined distance, which is determined by the distances it is desired to shift the color plate when a new plate is put in the furniture.

Having described my invention what I claim is:—

1. A register plug comprising a body having a hole surrounded by body material extending transversely therethrough its entire thickness; a non-revolute bearing bar longitudinally movable in the hole in said body, said bar having a head exterior the body; revolute means within said body and bar to

move said bar; and means to hold said revolute means in said body. 25

2. A register plug comprising a body having a transverse opening therethrough, said opening being enlarged at one end, and said body being cut away at one side adjacent to said opening, said body having a spline-way in one side thereof; a bearing bar having a spline in one side thereof, said bar and spline being adapted to fit into and move longitudinally in the opening of said body, said bearing bar having a central screw threaded bore; a screw threaded bolt in said bore, said bolt having a head provided with transverse channels; and a cap plate secured to said body and covering said bolt. 35

In witness that I claim the foregoing I have hereunto subscribed my name this 30th day of March, 1907.

HARRY H. PORTER.
